UNITED STATES PATENT OFFICE.

HAROLD FROST HEWETSON, OF YOUNGSTOWN, OHIO, ASSIGNEE, BY MESNE ASSIGNMENTS, TO TRUSCON STEEL COMPANY, OF YOUNGSTOWN, OHIO, A CORPORATION OF MICHIGAN.

SHEET-FEEDING GUIDE FOR EXPANDING MACHINES.

Application filed September 27, 1924. Serial No. 740,312.

This invention relates to machines for making expanded metal, and more particularly to the sheet feeding and guiding means for transferring the slotted blank from the 5 slitting or cutting machine to the expanding machine.

In the manufacture of expanded metal lathing and the like, it is customary to use a long narrow blank of metal which is cut 10 or slit to provide rows of alternating slits throughout the length of the blank, and this slotted blank is fed to the expanding machine. The manner in which the slotted blank is fed from the slitting device to the 15 expanding mechanism is of particular importance because the cutting and slitting instrumentalities preferably operate on the sheet while it is in the horizontal plane while the preferred expanding instrumentalities operate on the sheet while held in 20 a vertical plane. Thus, during the transfer of the slotted blank from the cutting machine to the expanding machine, it is necessary to rotate the same through an angle 25 of 90°, and since this movement must be accomplished quickly and accurately to maintain the capacity of the machines, it is necessary to provide efficient means for properly conveying the sheet from the slitting 30 station to the expanding station continuously and without buckling or binding in the guideway.

Accordingly, the present invention has particularly in view a novel sheet feeding 35 guide which allows the sheet to turn freely as it slips forward over a guiding surface which gives the sheet the required freedom of turning without producing internal stresses. In other words, the invention provides 40 a means which will permit the slotted blank to readily twist or warp in its movement but on the other hand will always have sufficient freedom to prevent buckling.

A further object of the invention is to 45 provide a guideway which will compel the sheet to turn or rotate about a longitudinal axis which therefore becomes the center of rotation. During this turning or rotating movement the sheet becomes both warped 50 and dished to a sufficient extent to loosen up the slits of the blank in such a way that the opening of the sheet into meshes by the expanding mechanism is facilitated.

With the above and other objects in view

which will more readily appear as the nature 55 of the invention is better understood, the same consists in the novel construction, combination and arrangement of parts herein-after more fully described, illustrated and claimed.

A preferred and practical embodiment of 60 the invention is shown in the accompanying drawings, in which:

Figure 1 is a diagrammatic top plan view 65 illustrating the application of the invention.

Figure 2 is a diagrammatic side elevation of the parts shown in Figure 1.

Figure 3 is a diagrammatic view illustrating the progress of the slotted blank 70 through the guide and associated machines.

Figure 4 is a diagrammatic view illustrating the manner in which a transverse element of the sheet is turned or rotated transversely in moving from a horizontal to 75 a vertical plane.

Figure 5 is a top plan view of the guide constituting the present invention.

Figure 6 is a diagrammatic side elevation of the improved guide.

Figure 7 is an elevation of the discharge 80 end of the guideway.

Figure 8 is a vertical cross-sectional view taken on the line 8-8 of Figure 6.

Similar reference characters designate corresponding parts throughout the several 85 figures of the drawings.

The present invention possesses special utility as a component part of a sheet metal expanding machine, particularly when combined and coordinated with a rotary cutter 90 functioning as the slitting device of the machine and also as a propelling means to direct and feed the slotted sheet toward the expanding mechanism. The general relation of that combination is shown in Figs. 95 1 and 2 of the drawings wherein the rotary cutter is designated generally by the reference letter C and comprises the upper and lower cutting rolls C¹ and C², and the expanding mechanism designated generally by 100 the reference letter E.

The rotary cutter and the expanding mechanism are arranged at a distance apart, and between these devices is arranged the present novel sheet feeding guide which 105 operates therewith, the receiving end of the guide being disposed in proximal relation to the delivery side of the cutter C and the

delivering or feeding end of the guide being arranged in proximal relation to the receiving end of the expanding mechanism. The expanding mechanism may be of any suitable type, but preferably is of the type employing the shouldered dies *e* and stepped deflector disks *d* having the relation and function disclosed in the patent of Joseph A. Halls No. 1,505,388, dated August 19, 10 1924.

A primary function of the sheet feeding guide *G* arranged in the relation described is to evenly, progressively and rapidly transfer the slotted blanks from the horizontal plane of the slitting device or cutter *C* to the vertical receiving-guideway of the expanding mechanism. In practice the elongated metal blank is operated upon by the cutting rolls *C*¹ and *C*² to thereby produce an elongated slotted blank *B* which after passing through the strippers *S* is fed into the guide *G* where it is automatically propelled through with the necessary freedom to prevent buckling. Preferably, the front end of the following sheet is overlapped with the rear end of the leading sheet and the same are thus automatically propelled or fed through the guideway by the feeding action of the cutting rolls until they reach the zone of the expanding machine which is also provided with feeding or advancing rollers.

As shown in Figures 1 and 2, the blank is slotted by the cutting rolls *C*¹ and *C*² in a horizontal plane and is then passed into the receiving end *G*¹ of the guide *G*. As will be observed from Figures 5 and 6 the said guide *G* preferably comprises a turning plate 1 which is horizontally disposed at the receiving end *G*¹, and is supported by a base 2 which extends throughout the length of the device and cooperates with a vertical wall 3 lying opposite the turning plate 1, thereby providing a continuous trough or groove 4 which guides the lower edge of the metal blank and to a certain extent holds the same while the upper edge remains free to follow the surface of the turning plate 1.

At the receiving end *G*¹ the said guide device *G* is provided with the upper and lower directing or guard plates 5 and 6 which overlie the horizontal portion of the turning plate 1 as well as the preliminary part thereof to insure that the sheet is initially directed into the groove 4 adjacent the vertical wall 3. After the slotted blank has been given its preliminary transversely warped and dished set by passing through the guard plates 5 and 6, the same will continue along the turning plate 1 in the manner indicated in Figures 3 and 4.

When the sheet leaves the cutting and slitting rolls *C*¹ and *C*² it is taken into the receiving end *G*¹ of the guide device *G* in the

flat plane indicated at *K*, in Fig. 4 and as it proceeds along the turning plate 1 it successively assumes the positions *L*, *M*, *N*, *O*, *P*, *Q* and *R*, the latter being the vertical plane in which the sheet leaves the guideway and enters the expanding machine.

The four edges of the sheet are in substantially a warped plane between the position *K* of Fig. 4 and the position *R*, but at the positions *K* and *R* the sheet is shown as 75 in a flat plane. However, between the horizontal and vertical positions of the blank, the same is curved or warped transversely as indicated at *L*, *M*, *O*, *P* and *Q*, thus the whole blank is rotated while advancing from the horizontal plane *K* to the vertical plane *R* due to the set and contour of the turning plate 1 which compels the edge *x* of the blank to follow the bottom edge of the wall 3 while the opposite edge *y* of the sheet rises 80 gradually as it passes along the curved or twisted surface of the turning plate 1. The edge *y* of the sheet becomes released from the upper guiding plate 5 as soon as the end of the blank clears the same, and thus, except 85 for the preliminary transverse bending or warping given the sheet as it passes through the guard plates 5 and 6, the said sheet is free to follow the curvature of the turning plate 1 during the rest of its travel in the 90 guide. In that way injurious stresses and buckling are avoided in the blank, while at the same time the blank has been bent or warped transversely to a sufficient degree to loosen up the strands formed by the slits 95 in such a way that the deflecting rollers *d* of the expanding machine can more readily deflect and open up the strands into meshes by pushing the same against the dies *e*.

To assist in maintaining the sheet in the 100 groove or guideway 4 as it nears the discharging end of the guide device *G* a suitable guard roller 7 may be provided. This roller preferably has a grooved periphery, and its spindle is adjustably mounted in the 105 brackets 8 carried by the wall 3 and the turning plate 1.

From the foregoing it will be apparent 110 that the present invention provides a simple and practical feeding and turning device for a slotted metal blank which will permit the sheet to turn from a horizontal to a vertical plane without being forced in such a way as to cause objectionable buckling or otherwise set up injurious internal stresses in the 115 sheet.

Also it will be perceived that the invention also involves a novel method of preparing expanded metal sheets which consists first in feeding horizontally a blank metal strip to a slitting device producing slits therein, then feeding the horizontal slotted sheet longitudinally forward and simultaneously progressively rotating it from a horizontal to a vertical position and finally 120

causing the slotted blank to be moved from its vertical position through an expanding mechanism and delivered in an expanded condition substantially along a horizontal 5 plane.

Without further description it is thought that the features and advantages of the invention will be readily apparent to those skilled in the art, and it will of course be 10 understood that changes in the form, proportion and minor details of construction may be resorted to, without departing from the spirit of the invention and scope of the appended claims.

15 I claim:

1. A sheet feeding device for expanding machines including a guideway having a substantially horizontal portion and a substantially vertical portion and a guard roller

arranged about said substantially vertical 20 portion.

2. A sheet feeding device for expanding machines including a guideway having a substantially horizontal portion and a substantially vertical portion and a grooved 25 guard roller arranged about said substantially vertical portion.

3. A sheet feeding guide for expanding machines including a guideway having a turning plate of spiral convex form constituting the bottom thereof for rotating a slotted sheet on a longitudinal axis and a guard roller disposed about the upright part 30 of said guideway.

In testimony whereof I hereunto affix my 35 signature.

HAROLD FROST HEWETSON.
